UNITED STATES PATENT OFFICE.

GUSTAV EGLOFF, OF CHICAGO, ILLINOIS, ASSIGNEE TO UNIVERSAL OIL PRODUCTS COMPANY, OF CHICAGO, ILLINOIS, A CORPORATION OF SOUTH DAKOTA.

PROCESS FOR CRACKING PETROLEUM OIL.

Application filed October 18, 1923. Serial No. 669,451.

To all whom it may concern:

Be it known, that I, GUSTAV EGLOFF, a citizen of the United States, residing in the city of Chicago, county of Cook, and State of Illinois, have invented certain new and useful Improvements in Processes for Cracking Petroleum Oil, of which the following is a specification.

This invention relates to improvements in process and apparatus for cracking petroleum oil, and has for its object the cracking of the maximum of light hydrocarbon oil by causing the oil to pass through controlled reaction paths or chambers.

The invention will be understood from the following description, reference being had to the accompanying drawing, in which the single figure represents a somewhat diagrammatic side elevation and vertical section of my improved apparatus.

Referring to the drawings (1) designates the furnace, in which is mounted heating coil (2), which, if desired, may take the form of 2,000 feet or more of four inch cycle tubing.

The oil is delivered to the coil by feed pump (3) and feed line (4) and discharged from the coil through transfer line (5). The transfer line (5) is provided with a branch (6) having control throttle valve (7) leading to a primary expansion chamber (8). The transfer line (5) is also provided with a branch line (9) having control valve (10), which line (9) leads to the lower end of a second expansion chamber (11). The expansion chamber (8) is connected at its end remote from the inlet pipe (6) with the chamber (11) by means of transfer line (12) having control valve (18). The expansion tank (11) is provided with liquid residue drawoff pipe (14) controlled by valve (15) and at its upper end with vapor pipe (16) having throttle valve (17), which pipe (16) leads to the lower portion of dephlegmator (18). Dephlegmator (18) is provided with the usual baffles (19) and at its upper end with vapor outlet pipe (20) having throttle valve (21), which pipe leads to condenser coil (22) seated in box (23).

The lower end of condenser coil 22, is connected by pipe (24) to the upper end of receiver (25), which receiver (25) is provided with a gas control valve (26) and a liquid control valve (27); reflux condensate is drawn off from the lower end of dephleg-

mator (18) by means of pipe (28) and returned to feed line 4. More or less of the reflux condensate can be diverted from the system, if desired, through branch (29) by suitably controlling the valves (30) and (31) in pipes (29) and (28) respectively.

Carrying out the invention the oil is fed through coil (2) where it may be heated to a temperature of 800° F. or more, and subjected to a pressure of say 200 to 2,000 pounds per square inch. A regulated portion of the hot oil is passed directly to the tank (8) and the remainder of the hot oil is passed through the pipe (9) directly to the tank (11). This is accomplished by suitably regulating the valves (7), (10) and (13).

The substantial vaporization takes place in the expansion chamber (11). All of the contents of chamber (8) pass into chamber (11). The chambers (8) and (11), as well as the balance of the system, may be maintained under the same pressure as coil (2), or a lower pressure, if desired, in which event a pump (32) may be interposed in the branch line (28'); valves (33) and (34) being then opened and valve (35) closed. This is done in order to permit the return of reflux condensate back to the heating coil (2).

By means of the present apparatus and process a large amount of oil at a high velocity can be passed from coil (2), but chamber (8) cannot be made sufficiently large to take care of all of the oil, and at the same time withstand the pressure at the operating temperatures. Accordingly, a portion of the hot oil is bypassed around the tank (8) and into chamber (11). This gives you more reacting space, while at the same time permitting the use of an expansion chamber such as chamber (8) through which the bulk of oil is passed, and in which part of the reaction takes place. The reaction is finally completed in the larger chamber (11).

It is to be clearly understood that only so much of the oil is passed through the line (9) as the tank (8) cannot take care of.

I claim as my invention:

1. A process of cracking oil, consisting in passing the oil through a heating coil where in it is subjected to cracking conditions of heat and pressure, in transferring a portion of the oil from said coil into a primary expansion chamber, in directing all of the oil constituents from said primary expansion chamber to a secondary chamber, and in in-

2. introducing the remaining portion of the heated oil from said coil directly into the liquid oil in said secondary expansion chamber to increase the conversion therein.
5. 2. A process of cracking oil, consisting in passing the oil through a heating coil where-
in it is subjected to cracking conditions of heat and pressure, in transferring a portion of the oil from said coil into a primary ex-
pansion chamber, in directing all of the oil constituents from said primary expansion chamber to a secondary chamber, and in in-
troducing the remaining portion of the heated oil from said coil directly into the liquid oil in said second expansion chamber to increase the conversion therein, in taking off vapors from said second expansion chamber, in dephlegmating such vapors, in condensing the dephlegmated vapors and collecting the resulting distillate, and in returning the reflux condensate resulting from the dephleg-
mation of the vapors to the heating coil for further treatment, and in continuously with-
drawing unvaporized carbon-containing residual oil from said second expansion chamber to be isolated from the system.
10. 3. A process of cracking oil, consisting in passing the oil through a heating coil where-
in it is subjected to cracking conditions of heat and pressure, in transferring a portion of the oil from said coil into a primary ex-
pansion chamber, in directing all of the oil constituents from said primary expansion chamber to a secondary chamber, and in in-
troducing the remaining portion of the heated oil from said coil directly into the liquid oil in said second expansion chamber to increase the conversion therein, in taking off vapors from said second expansion chamber, in dephlegmating such vapors, in condensing the dephlegmated vapors and collecting the resulting distillate, and in returning the reflux condensate resulting from the dephleg-
mation of the vapors to the heating coil for further treatment, and in continuously with-
drawing unvaporized carbon-containing residual oil from said second expansion chamber to be isolated from the system.
15. 4. A process of cracking oil, consisting in passing the oil through a heating coil where-
in it is subjected to cracking conditions of heat and pressure, in transferring a portion of the oil from said coil into a primary ex-
pansion chamber, in directing all of the oil constituents from said primary expansion chamber to a secondary chamber, and in in-
troducing the remaining portion of the heated oil from said coil directly into the liquid oil in said second expansion chamber to increase the conversion therein, in taking off vapors from said second expansion chamber, in dephlegmating such vapors, in condensing the dephlegmated vapors and collecting the resulting distillate, and in returning the reflux condensate resulting from the dephleg-
mation of the vapors to the heating coil for further treatment, and in continuously with-
drawing unvaporized carbon-containing residual oil from said second expansion chamber to be isolated from the system.
20. 5. A process of cracking oil, consisting in passing the oil through a heating coil where-
in it is subjected to cracking conditions of heat and pressure, in transferring a portion of the oil from said coil into a primary ex-
pansion chamber, in directing all of the oil constituents from said primary expansion chamber to a secondary chamber, and in in-
troducing the remaining portion of the heated oil from said coil directly into the liquid oil in said second expansion chamber to increase the conversion therein, in taking off vapors from said second expansion chamber, in dephlegmating such vapors, in condensing the dephlegmated vapors and collecting the resulting distillate, and in returning the reflux condensate resulting from the dephleg-
mation of the vapors to the heating coil for further treatment, and in continuously with-
drawing unvaporized carbon-containing residual oil from said second expansion chamber to be isolated from the system.

GUSTAV EGLOFF.

- introducing the remaining portion of the heated oil from said coil directly into the liquid oil in said secondary expansion chamber to increase the conversion therein.
5. 2. A process of cracking oil, consisting in passing the oil through a heating coil wherein it is subjected to cracking conditions of heat and pressure, in transferring a portion of the oil from said coil into a primary expansion chamber, in directing all of the oil constituents from said primary expansion chamber to a secondary chamber, and in introducing the remaining portion of the heated oil from said coil directly into the liquid oil in said second expansion chamber to increase the conversion therein, in taking off vapors from said second expansion chamber, in dephlegmating such vapors, in condensing the dephlegmated vapors and collecting the resulting distillate, and in returning the reflux condensate resulting from the dephlegmation of the vapors to the heating coil for further treatment.
10. 3. A process of cracking oil, consisting in passing the oil through a heating coil wherein it is subjected to cracking conditions of heat and pressure, in transferring a portion of the oil from said coil into a primary expansion chamber, in directing all of the oil constituents from said primary expansion chamber to a secondary chamber, and in introducing the remaining portion of the heated oil from said coil directly into the liquid oil in said second expansion chamber to increase the conversion therein, in taking off vapors from said second expansion chamber, in dephlegmating such vapors, in condensing the dephlegmated vapors and collecting the resulting distillate, and in returning the reflux condensate resulting from the dephlegmation of the vapors to the heating coil for further treatment, and in continuously withdrawing unvaporized carbon-containing residual oil from said second expansion chamber to be isolated from the system.

GUSTAV EGLOFF.

DISCLAIMER

1,561,779.—*Gustav Egloff*, Chicago, Ill. PROCESS FOR CRACKING PETROLEUM OIL. Patent dated November 17, 1925. Disclaimer filed January 2, 1934, by the patentee, the assignee, *Universal Oil Products Company*, approving and concurring.

Hereby enters this disclaimer to the subject matter constituting claims 1 and 2 of the patent, which read as follows:

“1. A process of cracking oil, consisting in passing the oil through a heating coil wherein it is subjected to cracking conditions of heat and pressure, in transferring a portion of the oil from said coil into a primary expansion chamber, in directing all of the oil constituents from said primary expansion chamber to a secondary chamber, and in introducing the remaining portion of the heated oil from said coil directly into the liquid oil in said secondary expansion chamber to increase the conversion therein.

“2. A process of cracking oil, consisting in passing the oil through a heating coil wherein it is subjected to cracking conditions of heat and pressure, in transferring a portion of the oil from said coil into a primary expansion chamber, in directing all of the oil constituents from said primary expansion chamber to a secondary chamber, and in introducing the remaining portion of the heated oil from said coil directly into the liquid oil in said second expansion chamber to increase the conversion therein, in taking off vapors from said second expansion chamber, in dephlegmating such vapors, in condensing the dephlegmated vapors and collecting the resulting distillate, and in returning the reflux condensate resulting from the dephlegmation of the vapors to the heating coil for further treatment.”
